(57) **CLAIM**

The ornamental design for a roll towel dispenser lockout, as shown and described.

DESCRIPTION

FIG. 1 is an exploded front, top and left side perspective view of a first embodiment of a roll towel dispenser lockout; FIG. 2 is an exploded front, top and right side perspective view thereof;

FIG. 3 is an assembled right side elevation view thereof. FIG. 4 is an assembled front, top and right side perspective view thereof;

FIG. 5 is an exploded front, top and left side perspective view of a second embodiment of a roll towel dispenser lockout;

FIG. 6 is an exploded front, top and right side perspective view thereof;

FIG. 7 is an assembled right side elevation view thereof; and,

FIG. 8 is an assembled front, top and right side perspective view thereof.

The broken lines in the drawings illustrate portions of the roll towel dispenser lockout and form no part of the claimed design.

1 Claim, 8 Drawing Sheets
